UNITED STATES PATENT OFFICE.

ALBERTO CIMOROSI, OF BRAINTREE, MASSACHUSETTS.

TOY TORPEDO.

Application filed December 30, 1920. Serial No. 434,064.

To all whom it may concern:

Be it known that I, ALBERTO CIMOROSI, a subject of the King of Italy, and resident of Braintree, county of Norfolk, State of

Massachusetts, have invented an Improvement in Toy Torpedoes, of which the following description, in connection with the accompanying drawing, is a specification, like characters on the drawing representing like parts.

This invention relates to improvements in torpedoes, and particularly toy torpedoes, and the object thereof is to provide a torpedo, preferably of spheroidal shape which can be conveniently made at a minimum cost.

A further object of the invention is to provide a toy torpedo which will explode upon impact, but which can be safely handled and not explode except when projected with considerable force against a resisting object.

A further object of the invention is to provide a torpedo in which the explosive materials will be protected from the deteriorating influence of moisture and other conditions of the atmosphere.

A further object of the invention is to provide a torpedo with an enclosing substantially non-resilient shell which will so distribute the pressure, produced by impact, as to cause a more instantaneous explosion of the fulminating composition.

A further object of the invention is to provide a novel and improved method or process of making torpedoes which consists in agglomerating a mass of granular material upon a cartridge containing, and preferably full of, a fulminating composition.

In the performance of the process the grains of material forming the shell desirably are agglutinated together and to the surface of the cartridge.

The shell of agglomerated granular material preferably is produced by rolling the cartridge about in a mass of granular material, the cartridge either being provided with a viscous coating of glue or other adhesive, or dropped into and rolled about in a mixture of granular material and adhesive of such consistency that the agglutinated material will progressively accumulate upon the material in a manner similar to the accumulation of snow upon a rolled snow ball.

Other objects and features of the inven-

tion will more fully appear from the following description and the annexed drawings and will be particularly pointed out in the accompanying claims.

A preferred embodiment of my invention and a diagrammatic illustration of a preferred method of producing the same is illustrated in the accompanying drawings, in which,

Fig. 1 is an elevation of a preferred spherical form of torpedo;

Fig. 2 illustrates in separated sections a preferred form of cartridge adapted to contain the charge of fulminating composition;

Fig. 3 is a diametrical sectional view of the torpedo illustrated in Fig. 1; and,

Fig. 4 is a diagrammatic illustration of a preferred process of agglomerating the granular substance upon the cartridge to form the shell.

The present invention is an improvement upon the invention disclosed in my prior Patent No. 1,199,775, granted October 3, 1916, for improvements in toy torpedoes. The invention disclosed therein comprised a toy torpedo having a shell formed of two hollow substantially hemispherical sections containing a central tubular member extending across the dividing plane between the hemispherical sections. This shell was filled with a fulminating composition and the shell sections secured together by a band encircling the sections transversely of the plane of their meeting edges.

In the construction of the torpedoes made in accordance with the disclosure of this patent it was found difficult to completely fill the shell so that the material would rattle more or less and might be subject to a premature explosion.

One of the objects of the present invention is to provide a cartridge which may be completely filled by a fulminating composition and which will be so enclosed in a protecting shell as to prevent access of moisture and other deleterious ingredients of the atmosphere from obtaining access to the fulminating composition.

A further feature of the invention consists in providing a shell of such a character as to afford a cushion which will prevent premature explosion if the torpedo is accidentally jostled or dropped. The shell preferably is composed of materials which pro-

- duce a substantially non-resilient covering of sufficient tenacity to distribute the force, produced by the impact of the torpedo against a solid object, in such a manner as 5 to act upon a large portion of the fulminate composition and thereby cause a more instantaneous and consequently more vigorous explosion than heretofore produced by such articles.
- 10 In the preferred embodiment of the invention disclosed herein a cartridge is employed which desirably may be cylindrical in form comprising a central tubular body section 1 and bottom and top caps or covers 15 2 and 3. These covers may comprise end portions 4 and 5 respectively which may be flat or convexedly curved outwardly. The sections 2 and 3 desirably are provided with flanges 6 and 7 respectively adapted to fit 20 telescopically upon the central body section 1. Alternatively the body portion 1 may be provided with an integral head and any suitable form of cap secured thereupon which may be adapted to permit the cartridge to be completely filled with a fulminating composition.

Any desirable fulminating composition may be employed in the production of a torpedo embodying my invention, it being 30 understood that the term "fulminating composition" is adapted to include any compound composition or mixture adapted upon impact of the torpedo with a relatively solid substance to cause an explosion of such composition or mixture.

A preferred fulminating composition may comprise a mixture of chlorate of potash, sulphur and antimony, preferably small gravel stones or other solid objects being 40 intermingled therein.

The cartridge when filled and assembled is provided with a shell comprising an agglomerated mass 8 of granular material which covers, and preferably adheres to, 45 every part of the exposed wall of the cartridge. The shell may be constructed and applied by covering the cartridge with a coating of viscous adhesive material 9, such as glue or other adhesive and applying the 50 granular material thereto. Preferably, however, the filled cartridge, either in the coated or uncoated state is dropped into a mixture of granular material and adhesive of such consistency that it will accumulate upon the 55 cartridge when the latter is rolled in it so that the agglomerated granular material will accumulate upon the cartridge in a spheroidal or substantially spherical form.

In Fig. 4 of the drawing a filled cartridge 10 is illustrated as being rolled through a mass of finely granular material and adhesive 11 of such consistency that it will accumulate upon the surface of the cartridge in a spheroidal form. Such accumulation can be caused either by rolling

the cartridge in various directions, or by reciprocating the support for the granular material, such as a pan 12, in such a manner as to cause the cartridge to roll around in it in different directions.

The agglutinated granular material first adhering to the cartridge will provide a thin layer, somewhat increasing the diameter of the article and causes the same to begin to assume a spherical form 13 as illustrated in Fig. 3, and further rolling of the cartridge will eventually accumulate a sufficient amount of the agglutinated granular material to produce an article 15 of spheroidal or substantially spherical form.

When a sufficient amount of the granular material has agglomerated upon the cartridge it is removed and dried and, if desired, given a waterproofing coating of any desired color.

By producing the torpedo in the manner above described a substantially spherical article is provided having centrally embodied in it the cartridge containing the explosive material. Inasmuch as the explosive or fulminating composition, such as that above described, must be confined in order to explode, the torpedo thus produced is a most satisfactory article since the enclosing shell of agglomerated material, while being substantially non-resilient, is sufficiently tenacious to produce a pressure over a sufficient area of the fulminating material to cause substantially instantaneous explosion thereof.

Any suitable granular material may be employed in the construction of the shell of the torpedo. A preferred composition comprises finely comminuted fibrous material such as sawdust intermingled with a glue or other adhesive material of a permanent nature which when dried will produce a substantially solid mass.

In the practical performance of the process the cartridges may be dropped into a pan of sawdust and a sufficient amount of glue applied to the cartridge and to the sawdust to cause the cartridge when rolled about in the sawdust, by oscillating the pan, to form a spherical, or spheroidal shell upon the cartridge.

It will be understood that the embodiment of the invention disclosed herein is illustrative and not restrictive and that the torpedo may be made in any desirable form and that the agglomerated mass forming the shell thereof may be produced in any suitable manner. It will also be understood that any other form of cartridge may be employed or that the fulminate may itself be so composed that it may be enclosed within an agglomerated shell without requiring an enclosing sheath or carton and that other modifications may be made within the spirit and scope of the following claims.

Having thus described my invention, what

I claim as new, and desire to secure by Letters Patent, is:

1. A torpedo comprising a shell formed of a mixture of an agglutinant and a granular material and having a central cavity containing a fulminating composition.
2. A torpedo comprising a cartridge filled with a fulminating composition and having a spheroidal shell formed of a mixture of an agglutinant and a granular material.
3. A torpedo comprising a substantially cylindrical cartridge completely filled with a fulminating composition having a spheroidal shell formed of a mixture of an agglutinant and a comminuted fibrous material.
4. A torpedo comprising a cartridge having a central tubular member filled with a fulminating composition having a spheroidal shell formed of a mixture of an agglutinant formed of granules of material agglutinated together and to said cartridge.
5. The process of making torpedoes which

consists in filling a cartridge with a fulminating composition and agglomerating thereon a shell of agglutinated granular material upon said cartridge by means of a suitable adhesive.

6. The process of making torpedoes which consists in filling a cartridge with a fulminating composition and coating said cartridge with an agglomerated mixture of granular material and an adhesive by rolling the cartridge in said granular mixture to form a substantially spheroidal shell thereupon.
7. The process of making torpedoes which consists in filling a cartridge with a fulminating composition and causing the same to roll in a mixture of sawdust and adhesive to form a spheroidal shell upon said cartridge.

In testimony whereof, I have signed my name to this specification.

ALBERTO CIMOROSI.

Patent No. 1,467,755.

September 11, 1923.

ALBERTO CIMOROSI.

It is hereby certified that error appears in the printed specification of the above numbered patent requiring correction as follows: Page 3, lines 18 and 19, claim 4, strike out the words and syllable "having a spheroidal shell formed of a mixture of an agglu-" and insert instead and provided with enclosing heads and an enclosing shell; and that the said Letters Patent should be read with this correction therein that the same may conform to the record of the case in the Patent Office.

Signed and sealed this 15th day of January, A. D. 1935.

Leslie Frazer
